COVER FOR COOKING PANS OR THE LIKE

Milton L. Heiser, Wayzata, and David Eriksen, Minneapolis, Minn., assignors to Fingerhut Corporation, Minnetonka, Minn.

Filed Nov. 15, 1972, Ser. No. 306,934

Term of patent 14 years

Int. Cl. D7—02

U.S. Cl. D7—131

FIG. 1 is a top perspective view of a cover for cooking pans or the like showing our new design;

FIG. 2 is a top plan view thereof;

FIG. 3 is a bottom plan view thereof;

FIG. 4 is an elevational view thereof;

FIG. 5 is an enlarged, partial sectional view according to section lines 5—5 in FIG. 3.

The vent holes randomly shown in FIGS. 1—3 are continuous about the entire periphery in the path indicated by the broken lines therein as represented in FIG. 4.

We claim:

The ornamental design for a cover for cooking pans, or the like, as shown and described.
